COMBINED TOWEL AND SOAP SUPPORT FOR MOUNTING ON A SHOWER DOOR

Claude C. Campbell, Lomita, Calif., assignor to Yolanda Art, Inc., Hawthorne, Calif., a corporation of California

Filed Sept. 13, 1961, Ser. No. 66,713

Term of patent 14 years

(Cl. D4—3)

FIGURE 1 is a perspective view of a combined towel and soap support for mounting on a shower door showing my new design;

FIG. 2 is an end elevational view thereof taken from the left side of FIG. 1;

FIG. 3 is an end elevational view thereof taken from the right side of FIG. 1; and

FIG. 4 is a bottom plan view thereof.

I claim:

The ornamental design for a combined towel and soap support for mounting on a shower door, as shown.
